UNITED STATES PATENT OFFICE.

LLOYD G. COPEMAN, OF FLINT, MICHIGAN.

REFRIGERATOR DOOR.

Application filed December 20, 1923. Serial No. 681,901.

To all whom it may concern:

Be it known that LLOYD G. COPEMAN, a citizen of the United States, residing at Flint, in the county of Genesee and State of

5 Michigan, has invented certain new and useful Improvements in Refrigerator Doors, of which the following is a specification.

This invention relates to a cast refrigerator door. The object of the present invention is to cast a tile door lining directly on a fibrous outer panel which provides a cheaper and lighter construction, the door having a dead air space in the interior which serves as a heat insulator.

10 Another object is to provide a mechanical union between the cast part of the door and the fibrous outer panel that is not readily broken. In fact, the tile and the outer panel are so secured and keyed together that it requires considerable effort to force the same apart. Another purpose of a door of this character is that the interior is formed with a smooth and glazed surface which may be enameled while the outer panel is of 15 fibrous material which is better adapted to receive the door hardware. By making a door on this principle, it is possible to cast the lining of the door onto an outer panel which is of different material. It is possible to 20 have an outer panel formed of a material of less heat conductivity for the purpose of insuring proper insulation to the interior of the refrigerator.

In the drawings:

25 Figs. 1 to 7 inclusive are views in section showing the steps in manufacturing the door.

Fig. 8 is a section on the line 8—8 of Fig. 7.

30 Fig. 9 is a detail in perspective of the reinforcing member.

Fig. 10 is a section on the line 10—10 of Fig. 9.

Fig. 11 is a detail of the blank which 35 forms the core.

Fig. 12 is a detail in perspective of one corner of the core.

Fig. 13 is a section on the line 13—13 of Fig. 12.

40 Referring to Figs. 1 to 7 inclusive, I have shown the successive steps in the manufacture. The first step is the placing of an inverted box-like core *a* on a fibrous outer panel *b* (refer to Fig. 11). This core is 45 formed from a blank of fibrous material or a fibre board, and comprises the main body

blank *c*, the end flaps *d* and the side flaps *e*. The end and side flaps are folded along the dotted lines *f*, the flaps again folded along the dotted lines *g* to form the flanges *h* 60 which are adapted to rest upon the fibrous outer panel. The sealing strips *i* are secured to the core at the corners when the blank is folded so as to seal the joints. After this box-like core has been placed in 65 position on the outer panel *b*, the same is preferably painted or coated with a layer of silicate of soda, designated *j*. This additionally seals all the joints and provides practically an air tight box. 70

The reinforcing frame *k* is provided with the flanges *m* and when the reinforcing frame is superimposed over the core, the sides of said reinforcing frame will be spaced a slight distance from the sides of the core. 75 This reinforcing frame has a series of holes *n* punched out in the side, for a purpose that will be hereinafter described. The flange *m* superimposed on the flange *h* of the core is then nailed or secured by screws 80 to the fibrous outer panel as at *o*, thus securing together the outer panel *b*, the core *a* and the reinforcing frame *k*.

Fig. 5 shows the die *p* superimposed over this outer panel and core, and in Fig. 6 the casting material has been poured into the die. However, the cement may be forced in under pressure. I prefer to use a casting material which is known as oxy-chloride cement, which I find well adapted to doors 85 of this character. This casting material is poured cold and the same will flow into the die and around the reinforcing member, the cement flowing through the holes *n* carried by the reinforcing member and into the 90 space between the reinforcing member and the core. In this way the reinforcing frame is keyed to the cast inner lining or tile and as the reinforcing frame is mechanically secured to the outer panel, obviously, the inner lining and the outer panel will be 95 mechanically united.

In addition to the mechanical union of the reinforcing member and the outer panel, the cement additionally possesses properties similar to glue and where the cement contacts with the fibrous outer panel, the same will adhere to the fibrous material of the panel. The cement will also penetrate the pores of the fibrous panel thus insuring a firm union. 100 When pressure is used for casting the lining, the cement will be forced into the pores 110

farther than when the same is merely poured. A fibrous (preferably wood) outer panel lends itself very readily to this form of union since the fibre has a great number of pores in which the cement may be forced. This latter condition and the permanent fastening of the reinforcing frame to the outer panel insures a perfect union between the two parts of the door.

10 As the door is withdrawn from the mold, there is formed a finished product having a fibrous outer panel and a cast stone inner lining or tile having a hollow interior. The air which is trapped in the interior forms 15 a dead air space which acts as a heat insulator. The making of the door of two parts, each of different material and possessing different characteristics, enables one to select a material for the outer panel such as 20 wood, or fibrous board, which has a low conductivity of heat.

The core α is made of fibre board or other light material, although I preferably use a fibrous material since this may be readily 25 handled, is relatively light in weight, and the cost is low. The reinforcing frame is made preferably of metal to provide sufficient rigidity to the mechanical union between the two parts of the door. The cement which flows through the large number 30 of punched-out holes n in the reinforcing frame assures the adhesion of the cement with the reinforcing frame, as when the cement hardens the reinforcing frame will be 35 securely anchored or keyed within the cement.

What I claim is:

1. In a door, the combination of an outer panel of a heat-insulating material, and a cast 40 hollow tile lining of non-heat-insulating material cast united thereto.
2. In a door, the combination of an outer panel and a hollow cast stone tile lining cast thereto the major portion of said lining 45 spaced from the outer panel to provide a dead air space.
3. In a door, the combination of an outer panel of one material, and a reinforced hollow cast tile lining united to the outer panel 50 by means of the reinforcement.
4. In a door, the combination of an outer

panel of one material, a cast stone hollow tile lining therefor provided with a reinforcement, the reinforcement being mechanically secured to the outer panel and embedded in the hollow tile casting.

5. In a door, the combination of an outer panel of one material and a hollow cast tile lining for the door of a different material cast with a reinforcing member keyed there- 60 to said reinforcing member being mechanically united to the outer panel.

6. In a door the combination of an outer panel of heat-insulating material a reinforcing frame fastened thereto and a cast stone 65 lining cast onto and concealing the said reinforcing frame and thereby united to the outer panel.

7. In a door the combination of a fibrous outer panel a slotted reinforcing frame 70 nailed to the outer panel and a cast stone tile cast onto the reinforcing frame.

8. In a door the combination of a fibrous outer panel and a hollow tile stonework inner lining cast onto the door the major 75 portion of said lining spaced from the outer panel.

9. In a door the combination of a fibrous outer panel and a hollow cast stone tile lining cast onto the inner side of the door 80 in substantially airtight relation the intermediate portion of said lining spaced from the panel to provide an intermediate dead air space.

10. In a door the combination of a fibrous outer panel and a hollow stone work tile lining provided with a hollow core member cast onto the inner face of the outer panel.

11. In a door, the combination of an outer panel of a heat-insulating material, and a 90 hollow tile lining cast onto the inner face of the door and provided with a paper board hollow core cast into the job.

12. In a door, the combination of an outer panel of heat-insulating material, and a 95 hollow tile lining therefor cast onto the inner face of the panel and provided with a silicated hollow paper board core cast into the job.

In testimony whereof I affix my signature.

LLOYD G. COPEMAN.
